UNITED STATES PATENT OFFICE

167,061

VEHICLE SPLASH GUARD

Albert Schwartz, Philadelphia, Pa., assignor to
Globe Rubber Products Corporation, Philadelphia, Pa., a corporation of Pennsylvania

Application October 23, 1951, Serial No. 17,075

Term of patent 14 years

(Cl. D14—6)

To all whom it may concern:

Be it known that I, Albert Schwartz, a citizen of the United States, residing in Philadelphia, county of Philadelphia, Commonwealth of Pennsylvania, have invented a new, original, and ornamental Design for a Vehicle Splash Guard, of which the following is a specification, reference being had to the accompanying drawings, which form a part thereof.

The figure is a perspective view of the vehicle splash guard showing my new design.

The rear of the vehicle splash guard, not shown, is substantially plain and unornamented.

I claim:

The ornamental design for a vehicle splash guard as shown, and described.

ALBERT SCHWARTZ.
